CONTROL SYSTEM

George W. Upp, Lakewood, Ohio, assignor to The
Midland Steel Products Company, Cleveland,
Ohio, a corporation of Ohio

Application May 6, 1941, Serial No. 392,085

5 Claims. (74—471)

This invention relates to new and useful improvements in control stations and more particularly to the type disclosed in my copending application Serial No. 353,495, filed August 21, 1940. This control station contemplates a structure in which a plurality of control valves can be conveniently mounted as a unit in the smallest possible space in the cab of the shovel, digger or the like.

An important object of the invention is to provide an arrangement whereby a single lever can control three separate operations; two of them simultaneously.

A further object of the invention is to provide in such an arrangement, means whereby at any point in the movement of the control handle for operating one or more valves, this handle can be moved to operate another valve without affecting the position of the first mentioned valves.

Another object of the invention is to provide simple and efficient cam means for opening or in closing a valve and for releasably retaining such valve either in open or closed position.

Other objects and advantages of the invention will become apparent during the course of the following description.

In the accompanying drawings forming a part of the description and wherein like numerals are employed to designate like parts throughout the several views,

Fig. 1 is a perspective view of the valve control stand shown in my copending application Serial No. 353,495, upon which the present invention is an improvement.

Fig. 2 is a top plan of the same.

Fig. 3 is an enlarged vertical transverse section of the upper portion of the stand taken on the line 3—3 of Fig. 2.

Fig. 4 is an enlarged fragmentary section taken on the line 4—4 of Fig. 3.

Fig. 5 is an enlarged longitudinal section of a non-compensating type of poppet valve employed in the invention.

Fig. 6 is an enlarged fragmentary section of this valve taken on the line 6—6 of Fig. 5.

Fig. 7 is a front elevation of a pair of such valves arranged as a unit with cam actuation.

Fig. 8 is a top elevation of the same with one-half of the structure shown in section taken along the line 8—8 of Fig. 7.

Fig. 9 is a side elevation of the forward portion of the valve showing a side elevation of the cam actuator.

Referring now more particularly to the draw-

ings for a detailed description of the invention, which is designed for the easier, more positive and quicker operation of the usual power operated shovel controls by means of a pressure medium, the numeral 9 designates a unitary control station in its entirety. This station comprises a stand 10 which is built separate and independent of the power operated shovel and its controls, and is installed as a unit in the limited space in the shovel cab to be connected to the various shovel controls by flexible hose connections to air operated actuators of the usual construction. These actuators, not shown, are operated by a pressure medium under the control of operating levers A for the swing and propel mechanism; B for the jaw clutches of the swing and propel mechanism; C for the crowd and retract mechanism; D for the steering mechanism; E for the hoist mechanism; F for the boom hoist mechanism; G for the engine clutch; H for the swing brake mechanism and I for the propel brake mechanism. These various mechanisms are standard on power shovels and are well understood by those skilled in the art. All five levers 15 A to H inclusive, extend vertically through and operate longitudinally in individual slots 11 extending transversely across the top of the unitary stand. Each valve handle A to F, with the exception of handle E for the hoist mechanism, is adapted to alternately operate a pair of spring returned pressure control valves 13 and 14 of the compensating type shown in the aforesaid copending application and each with a return spring 14', as indicated in Fig. 3, although in instances where desired, these two valves or one of them may be of the non-compensating type such as is shown in Figs. 5 to 9 herein. When any of these five handles are moved from their normal neutral positions held by the opposed springs 20 of the two valves 13 and 14, these valves are alternately opened and closed, that is to say, when the operating handle is moved forwardly of the stand through its respective slot 11, the valve 14 is opened to permit passage of pressure, and when moved toward the rear end of its respective slot 11, the upper valve 13 is opened for the passage of pressure while the valve 14 returns to a closed position to cut off pressure therethrough.

In order to lock any of the operating handles and one valve of any pair in applied position, any of the slots 11 in which this operation is desired, may be covered by appropriately slotted interchangeable plates 13'. For illustration purposes such a plate is shown as having a longitudinally extending slot 14 through which projects and

operates the shank 15 of the operating handle for alternately opening and closing the two valves 13 and 14. The two ends of this longitudinal slot 14 are provided with lateral ways 16 extending entirely across the slot 11 in the top 12 of the stand and terminate in angular longitudinally extending ways 17 parallel with the slot 14 so that the operating handle can be moved through the slot 14 to operate either valve 13 and 14 and while so operated, this handle can be moved laterally through the way 16 to operate a third valve and down into the terminus 17 to be locked in said operating position until subsequently released by the operator. If desired any plate 13' can be omitted whereby the operating lever can be moved sidewise to control an auxiliary adjunct irrespective of the position of the operating lever, or other forms of a plate 13' shown in Fig. 2 (some with only an intermediate notch 13D with the ends of the plate spaced inwardly of the ends of slot 11, or as 13E with only one end lateral way) may be used where certain operations are desired, on any of the slots 11.

In order for any of the operating levers to be capable of both longitudinal and lateral swinging movement, it is made of an upper section having a lower forked end 18 which straddles and is pivoted to the upper end of the lower lever section 19 by means of a pivot pin 20, permitting the upper section of the lever to swing on this pivot laterally through the ways 16 of the slot. To normally urge the upper portion of this lever toward the right hand edge of the slot 14, a looped coil spring 21 has its intermediate portion 22 engaging the lower section 19 at one side of the pivot 20 with its two ends coiled about the pivot 20 and bent laterally to engage a corresponding side of the upper forked section 18, so that when the upper section of the lever is moved into either of the ways 16, the ends of this spring will be moved to the left of Fig. 4 to force the intermediate portion 22 firmly against the side of the lower section 19 to stress the spring, so that when pressure on the upper portion of the lever is released, this spring will return it to normal position into axial alignment with the lower section 19.

This lower section 19 of the lever is fulcrumed at 23 between the ears of a post 24 secured to a supporting bracket 25 fastened to the down-turned flange of the top 12 and to a transverse bar 26 connected with the legs of the stand as disclosed in my co-pending application. The end of the lever section 19 below the fulcrum 23 is angularly disposed at 27 and is pivotally connected as at 32 to a valve stem 28 of the lower valve 14. The valve stem 29 of the upper valve 13 is pivotally connected as at 30 above the fulcrum 23 the same distance therefrom as the pivot 32 for the valve stem 28. Thus, by moving the handle C lengthwise of the slot 14 in either direction, and in the plane of the pivot 20, the valves 13 and 14 can be alternately opened and closed.

In order that the dipper trip of the power shovel may be operated by the operating lever C, simultaneously with the crowd or retract movement of the shovel boom, a dipper trip valve J is mounted upon a bracket 35 depending from the underside of the top 12 of the stand. This dipper trip valve J is best shown in Figs. 4, 5 and 6 to be operated by lateral movement of the upper section 18 of the operating lever C. In order for this dipper trip valve J to be operated by the operating lever C at any point in its travel about its fulcrum 23, a valve operating plate 36 is made co-extensive with the length of the slot 11 in the stand top 12 and

is mounted by a yielding mounting in inclined relationship to the lever C, so that the upper end of the plate 36 is at all times in engagement with the upper laterally movable portion 18 of the operating handle C in all positions of the latter, to be operated thereby. Adjacent its lower end, the plate 36 is provided with a pair of somewhat semi-spherical or counter-sunk openings 37 at opposite side edges thereof to receive the conical or semi-spherical heads 38 of a pair of studs 39 secured to the lower portions of bracket 35 by means of the nuts 40. A compression coil spring 41 is placed upon each stud 39 between the bracket 35 and the valve operating plate so that the lower portion of this spring presses more firmly upon the valve plate 36 than its upper portion to hold the valve plate firmly in contact with the semi-spherical heads 38 and thereby form somewhat of a pivotal floating mounting for the plate.

The dipper trip valve J is provided with a longitudinally slidable plunger sleeve 42 terminating at its outer end in an enlarged head 43 which is normally forced outwardly against a stop ring 44 by a conical compression spring 45 to hold a ball 46 peened into the enlarged head 43, into engagement with the central portion of the valve operating plate 36 adjacent its upper edge. This normal exhaust position of the valve sleeve 42 will normally press the upper end of the valve plate 36 into engagement with the shank of the upper section of the operating lever C, so that when the latter is moved laterally into either way 16, the valve plate 36 will move the valve plunger sleeve 42 inwardly to permit pressure to pass through the valve J in a manner which will now be described.

The valve J is composed of a pair of sections 49 and 50 suitably bolted together with a packing therebetween, and the latter section 50 is provided with a bore 51 in which the valve sleeve 42 is slidably mounted. This section 50 is also provided with a lateral exhaust port 52 communicating with the bore and the interior of the sleeve 42 through the openings 53 in the latter whenever the sleeve is at the limit of its movement as shown in Fig. 5, to exhaust the valve. The inner end of the valve section 50 is provided with a recess for the reception of a suitable air tight packing 54 through which the valve sleeve 42 reciprocates.

The other valve section 49 is provided with a central pressure chamber 55 supplied with pressure through a suitable lateral pipe 56, which in some installations may be threaded in a central tapped opening in a closure cap 57. Extending co-axially within the chamber 55 is an annular valve seat 58 larger in diameter than the OD of the valve sleeve 42, and this seat at one side thereof and opposite the intake pipe 56, is provided with a port 59 into which is threaded a pipe 60 which leads to the actuator for the dipper trip. A floating inlet valve 61 is normally forced upon its seat 58 by means of the coil spring 62 so as to cut off the source of pressure from the port 59. In such position, and with the valve sleeve 42 disengaged from the inlet valve 61, the port 59 can exhaust through the valve sleeve, its ports 53 and escape into the exhaust port 52 to vent the mechanism operated by this valve. When the operating lever C is moved longitudinally in the slot 14 one way or the other to crowd or retract the shovel by the operation of the valves 13 and 14, and the upper section 18 of the operating handle C is moved laterally into either end 16 of the slot, the valve actuating plate 36 is caused to move toward its valve and

move the valve sleeve 42 into engagement with the inlet valve 61 and thereafter lift this valve from its seat so that pressure existing in chamber 55 may pass into the concentric seat 58 and thence to the port 59 to operate the dipper trip. It will be understood that in this position of the valve sleeve 42, its exhaust ports 53 will be closed by the bore of the valve section 50 thereby preventing escape of the pressure medium until the valve plate 36 is released by operating lever C. To retain the upper section 18 of the operating lever C in position to hold the inlet valve 61 open, this section of the operating lever is moved into the notched end 17 of the slot and will be held against one side thereof due to the pressure exerted on valve plate 36 by the valve spring 45. As soon as the operating lever C is moved into the lateral passage 16, the combined action of the valve spring 45 and the lever spring 21 will automatically throw the upper end of the control lever into the longitudinal slot 14 in which position it will be automatically moved back to its normal central position due to the opposed relation of the valves 13 and 14 acting on this lever when the operator releases it to the automatic operation of the mechanism. Due to the fact that the valve operating plate 36 is coextensive with the slot for the upper end of the operating lever, the latter may be moved to operate the dipper trip valve J regardless of the operating position of the control lever. With the inlet valve 61 seated and the end of the valve sleeve 42 touching the rubber gasket of this valve, it will be seen that the valve can be held in a lapped position.

While the trip valve operated by lateral movement of the operating lever is illustrated in connection with the particular crowd and retract lever C, it will be understood that it is within the purview of the invention to associate this valve with any of the levers A to F inclusive, or any lever assigned to control two or more operations simultaneously. In case it is desired not to employ compensating type valves 13 and 14, these may be replaced with the dual valve shown in Figs. 7 to 9 inclusive wherein a plain poppet type valve such as shown in Fig. 5 may be employed and the lower section of the operating lever C may be replaced with a cam operator with the upper section of the operating rod jointed or provided with a fulcrum like 20 to enable the upper end of the operating rod to move laterally, as the poppet valves are being manipulated through the main operating movement of the lever. Parts of this poppet valve which correspond to those shown in Fig. 5 are marked with corresponding reference numerals so as not to duplicate the description. Both of the valve bodies are mounted upon a bracket 35 and are supplied with a pressure medium through a common inlet manifold 70 terminating at opposite ends in end caps 71 so that the inlets into these valves are through the ends thereof rather than through the sides as shown in Fig. 6.

For alternately opening and closing the two valves, a cam segment 72 is pivotally mounted upon a stud 73 secured to the bracket 35 between the two valve casings. Above this pivot the cam is provided with a vertical boss 74 into which is threaded the lower end of a shank 75 of the operating lever C. As stated above, the upper end of this lever may be provided with a hinge joint 29 such as shown in the preceding modification for the operation of a third valve.

In order to releasably retain the operating lever

C in a neutral perpendicular position between the two valve casings, the upper edge of the cam is provided with a pair of openings 76 for the seating of the balls 46 in the valve sleeves 42. With the valve and cam assembled, both valve plungers 42 are depressed about .015 of an inch, and the balls in the plunger assemblies enter the small holes 76 in the cam by approximately .015 of an inch, thereby acting as detent balls to hold the lever in the neutral position and also to prevent any rattles. When the operating lever moves to either extreme as shown by the dot and dash lines in Fig. 7, the plunger sleeve valve of one valve is moved inwardly by the cam about $\frac{3}{2}$ of an inch thereby admitting tank pressure to the cylinder connected to that valve. At the same time, the cam moves entirely away from the other valve, leaving it in the released position. A second pair of small holes 77 is provided in the cam below the first pair, so that either one or the other plunger balls will also act as a detent when either valve is in applied position. Normally, the valve is mounted on the bracket with the handle lever or shank 75 extending through a slot which limits the cam rotation, but as an added safety measure, a pair of lugs 78 are provided at the lower portion of the cam segment which will alternately abut the valve housing as the lever is swung from one side to the other of its neutral position to also limit cam rotation when either of the valves is moved to applied position.

It is to be understood that various changes in the size, shape and relation of parts may be resorted to without departing from the spirit of the invention or the scope of the appended claims.

I claim:

1. The combination with a pair of movable elements; of an operating lever having its body fulcrumed at one end to operate one of said movable elements, said lever having its upper end movable independently of said body on an axis normal to the fulcrum axis and movable laterally of the normal plane of movement of said lever body to operate said other element, and an inclined operating plate for said second element co-extensive with the movement of said lever body, studs extending from the second element and having heads operating in openings in said plate, and coil springs on the studs between said plate and said second element.

2. The combination with a pair of spring pressed movable elements, and a third spring pressed element; of a single lever for operating all three movable elements and having its body fulcrumed and connected with said pair of elements to operate the same, the springs of said elements serving to retain said lever body in a neutral position, said lever having its upper end movable independently of the lever body on an axis normal to the fulcrum axis and movable laterally of the normal plane of movement of said lever body to operate said third element.

3. The combination with a pair of spring pressed movable elements and a third spring pressed element; of a single lever for operating all three movable elements and having its body fulcrumed and connected with said pair of elements to operate the same, the springs of said elements serving to retain said lever body in a neutral position, said lever having its upper end movable independently of the lever body on an axis normal to the fulcrum axis and movable laterally of the normal plane of movement of said lever body to operate said third element,

and an operating plate for said third element co-extensive with the movement of said lever body so as to be operated by the upper pivoted end of said lever in any position of said lever body.

4. The combination with a support having a slot, of a pair of spring pressed elements mounted below said slot in vertical alignment, an operating lever extending through said slot and having its lower end fulcrumed and pivotally connected to said elements on opposite sides of said fulcrum to maintain said lever in a neutral position, a third spring pressed element mounted below said slot to one side thereof, and the upper end of said lever engaging said third element to be normally urged thereby against one side of said slot and said upper end of the lever being movable transversely of said slot against the tension of said third spring pressed element in any angular position of said lever.

5. The combination with a support having a slot, a pair of movable elements mounted below

10 said slot and being movable at right angles to one another, an operating lever fulcrumed below said slot and adapted to be swung thereon to operate one of said elements, a bracket secured to said support below said slot and having a pair of studs extending from the bracket and terminating in semi-spherical heads, an operating plate for operating said other movable element and being mounted on said semi-spherical heads, a compression spring mounted upon each stud between its bracket and said operating plate, and an operating handle operating in said slot and connected to said operating lever on an axis normal to the axis of the fulcrum of the operating lever whereby when the operating handle is moved laterally of said slot the operating plate is moved to operate one of said movable elements when the operating lever is swung upon its fulcrum.

GEORGE W. UPP.
